UNITED STATES PATENT OFFICE

93,201

DESIGN FOR A SERVICE BAR BACK COUNTER

Clarence W. Brown, Chicago, Ill., assignor to
The Brunswick - Balke - Collender Company,
Chicago, Ill., a corporation of Delaware

Application November 16, 1933, Serial No. 49,753

Term of patent 3½ years

To all whom it may concern:

Be it known that I, CLARENCE W. BROWN, a citizen of the United States, residing at Chicago, in the county of Cook, State of Illinois, have invented a new, original, and ornamental Design for a Service Bar Back Counter, of which the following is a specification, reference being had to the accompanying drawing, forming part thereof.

In the drawing—

The figure is a perspective view of a service bar back counter showing my new design.

I claim:

The ornamental design for a service bar back counter as shown.

CLARENCE W. BROWN.
